[57] **CLAIM**

The ornamental design for a wheel trolley, as shown and described.

DESCRIPTION

FIG. 1 is a side perspective view of a wheel trolley showing my new design, the opposite side view being a mirror image of that shown;

FIG. 2 is a top plan view thereof;

FIG. 3 is a front elevational view thereof, with the rear support member locked in a vehicular member supporting position, and the front support member extended to receive a vehicular member;

FIG. 4 is a side perspective view thereof in a folded condition;

FIG. 5 is a rear elevational view thereof.

Fig. 3.

Fig. 4.

Fig. 5.
